UNITED STATES PATENT OFFICE.

GEORGE SENNETTE WING, OF ALEXANDER, NEW YORK.

PAIL-EAR.

SPECIFICATION forming part of Letters Patent No. 350,280, dated October 5, 1886.

Application filed March 11, 1886. Serial No. 194,839. (No model.)

To all whom it may concern:

Be it known that I, GEORGE SENNETTE WING, of Alexander, in the county of Genesee and State of New York, have invented a new and useful Improvement in Pail-Ears, of which the following is a specification, reference being had to the annexed drawings, forming a part thereof, in which—

Figure 1 is a side elevation, partly in section, of a pail provided with the improved ears. Fig. 2 is an enlarged perspective view of one of the pail-ears.

Similar letters of reference indicate corresponding parts in both figures of the drawings.

The object of my invention is to provide for pails a support by which the milkman can readily hold the pail while milking, to prevent the pail from coming in contact with the ground, and to guard against the tipping over of the pail.

The invention consists in a pail-ear provided with an outwardly-curved arm for supporting a pail, the ear proper being cut out from the said arm, all as hereinafter fully described, and pointed out in the claim.

The ear A is preferably formed of sheet metal, with the apertured body a and the apertured ear b, for receiving the bail B, by which the pail is carried. An arm, c, formed integrally with the ear b and cut from the metal from which the ear b is punched, is curved over away from the ear b approximately at

right angles to the body a of the ear, so that when the ear is applied to a pail the arm c will project outward away from the pail and form a convenient support, which may be received on the knees of the milkman, and which will readily sustain the pail without the necessity of exerting a great pressure upon the sides thereof. The pressure in the case of sheet-metal pails is destructive, besides involving an undesirable amount of labor in supporting the pail in the operation of milking.

Although I prefer to make the ear A with the auxiliary ear or arm c of sheet metal, it may be made of cast or malleable iron.

I am aware that ears for pails have been heretofore provided with auxiliary arms or ears for supporting the pail between the knees of the milkman, and I therefore do not broadly claim such invention.

Having thus described my invention, what I claim as new, and desire to secure by Letters Patent, is—

The herein-described pail-ear, consisting of the apertured plate A, the apertured ear b, punched from the plate, and the arm or knee support c, formed of the metal from which the ear b is punched, and bent over at approximately right angles to the plate, as set forth.

GEORGE SENNETTE WING.
